UNITED STATES PATENT OFFICE.

RAYMOND W. DULL, OF AURORA, ILLINOIS, ASSIGNOR TO STEPHENS-ADAMSON MFG. CO., OF AURORA, ILLINOIS, A CORPORATION OF ILLINOIS.

SETTLING-TANK.

1,005,522.

Specification of Letters Patent. Patented Oct. 10, 1911.

Application filed May 17, 1909. Serial No. 496,518.

To all whom it may concern:

Be it known that I, RAYMOND W. DULL, a citizen of the United States of America, and resident of Aurora, Kane county, Illinois, have invented a certain new and useful Improvement in Settling-Tanks, of which the following is a specification.

My invention relates to tanks for separating sand or gravel from water. The muddy water containing sand or gravel is discharged into the tank, and the water flows off in one direction while the sand or gravel is discharged by itself in another direction. The general operation of a tank of this kind is well understood.

Generally stated, the object of my invention is the provision of an improved and highly efficient settling tank of the aforesaid general character.

20 Special objects are the provision of an improved construction and arrangement whereby no fixed valves or equivalent devices will be necessary for discharging the sand or gravel; the provision of an improved construction and arrangement whereby no dividing partitions will be necessary for the tank—that is to say, whereby no ballast or ballasting-chamber will be necessary for the operation of the tank; to provide an improved construction and arrangement whereby the tilting of the tank is not essential to the operation thereof; to provide an improved construction and arrangement whereby no auxiliary frame with sand 35 and water spouts is necessary in the use of the tank for recovering sand or gravel from muddy water; and the provision of certain details and features of improvement and combinations tending to increase the general 40 efficiency of a settling tank of this particular character.

To the foregoing and other useful ends, my invention consists in matters hereinafter set forth and claimed.

45 In the accompanying drawings—Figure 1 is a front elevation of a settling tank embodying the principles of my invention. Fig. 2 is an enlarged detail sectional view of the valve mechanism thereof. Fig. 3 is 50 an enlarged fragmentary sectional view of the water-spout of the said tank. Fig. 4 is a view similar to Fig. 1, showing another form of my invention. Fig. 5 is a side elevation of the tank shown in either Fig. 1 or Fig. 4, the two being similar in appear-

ance when viewed from the side. Fig. 6 is a detail fragmentary view of the lower portion of the tank, showing the valve mechanism open.

As thus illustrated, and referring more particularly to Fig. 5, my invention comprises a tank A provided with a vertical front wall a and an inclined rear wall a', the two walls converging downwardly until they meet at their lower edges. Side walls a² are provided at their tops and at the rear end of the tank with knife-edge trunnions a³, which are preferably rectangular in cross section, whereby they can be turned around when one edge is worn out. The edges of these trunnions are adapted to rest in bearings B on the parallel frame beams C, between which latter the tank is disposed for operation. It will be seen that these trunnions a³ may be and preferably are as near the upper and rear end of the tank as possible, whereby the entire tank is adapted to swing up and down about an axis at its rear end, as distinguished from a tilting motion. The rear end of the tank is provided with a discharge-spout D for the water, and across its top a baffle-plate E is disposed in position to divide the upper area of the tank transversely, in the manner illustrated. The lower end of the tank is provided on the front face thereof with a discharge opening F, which latter is normally closed by a pivoted valve f. This valve is pivoted at its upper end at f', being mounted upon a casting f², which latter has an adjustable stop-screw f³, whereby the degree of motion of the valve is regulated in accordance with the character of the materials being handled. The action of this screw is better illustrated in Fig. 6, in which the valve is shown in its open position. The said casting f² is provided with an arm f⁴, upon which is adjustably mounted a weight f⁵. (See Fig. 5). A hanger rod G has its lower end pivoted to the casting f² at g, and has its upper end secured to a rocker bar g', which latter is supported in bearings g² on the stationary frame. It will be seen that this rocker bar g' has a knife-edge contact portion adapted to engage in the said bearings.

In operation, the muddy water is discharged into the tank in the direction indicated by the arrow in Fig. 5, the water, sand and gravel impinge against the face of the baffle-plate E, and the sand and gravel are

immediately precipitated to the bottom of the tank. The water overflows from the tank and is discharged therefrom by way of the spout D at the rear of the same. As soon as the weight of the sand and gravel is sufficient to over-balance the weight f^s , then the whole tank settles downward, causing the valve f to open and allow the contents to discharge into a bin or other receptacle. As soon as the discharge of sand and gravel has taken place, the reduction in the weight of the tank and its contents serves automatically to then close the valve f , as the weight f^s serves to raise the tank to its normal position, the leverage exerted by the arm f^s being sufficient for this purpose. In other words, the arm f^s and the casting f^2 serve as a lever, the pivotal point g being the fulcrum thereof. The weight f^s is sufficient to raise the tank when the latter is empty or filled with water. When sufficiently filled with sand or gravel, or with other material, the weight of the tank is then sufficient to raise the weight f^s , and this, of course, opens the said valve, permitting a partial discharge of the sand and gravel, the valve closing before any objectionable amount of water escapes. Thus the tank alternately rises and falls, and the sand and gravel are recovered from the muddy water. The water is discharged in one direction—that is to say, from the rear of the tank—while the sand and gravel are discharged from the front of the tank in the other direction. In this way no fixed valves or equivalent devices are necessary, and no tilting motion is necessary for the tank. By causing the water and sand to discharge in opposite directions, no receiving-spouts or troughs are necessary, as the sand and gravel can be dumped or discharged directly into bins or other receptacles for this purpose.

As shown in Fig. 4, the tank has straight sides, as distinguished from the downwardly tapering side walls of the tank shown in Fig. 1. Also in Fig. 4 the tank is provided with a plurality of valves H, which are in all respects the same as the one shown in the other figures, and above described. Further description of the multiple valve settling tank shown in Fig. 4 is, therefore, unnecessary. It may be stated, however, that by having a plurality of valves, the tank can be made much larger and of considerable length. Also separate bins or receptacles can be provided for receiving the discharge from the different openings. With a tank of this kind, I find that the sand and gravel are efficiently and satisfactorily separated from the water. No water, or at least very little, will be discharged by the valve, as the latter is very sensitive and closes promptly upon the slightest upward movement of the tank. It will be seen that the pivotal point g is below the pivotal point f^s ,

whereby the lifting power of the tank increases as it moves downward—that is say, the power of the tank to lift the weight f^s —the maximum leverage being exerted in the first instance. This is of considerable advantage, inasmuch as when the valve of the weight of the tank is decreasing rapidly owing to the discharge, and it is important that this decrease in the weight does not tend to prematurely stop the downward movement of the tank. In addition, the downward movement of the tank is effected by downward pull of the weight f^s , the lever at this time being exerted to the best vantage, as the lifting power or movement of the weight is rapidly increasing, the maximum lifting power being exerted at instant of final closure, and the closure of the valve being prompt and quick. When the tank moves down, the moment from f^s to f is increasing, while the moment from g to f^s is decreasing; and this condition is reversed when the weight f^s moves downward. The valve, it will be seen, is operated by the weight of the tank upon which it is carried.

I do not limit myself to the exact construction shown and described.

What I claim as my invention is:

1. In a settling tank, a movable receptacle a lever fulcrumed between its ends, connected at its shorter end for operating the receptacle, an adjustable weight for the longer end of said lever, a discharge opening for the receptacle, a valve for said discharge opening, a rigid connection between the valve and lever, whereby the valve is operated by movement of the receptacle, the valve having parallel axes one of which is the fulcrum of said lever.

2. In a settling tank, a movable receptacle a discharge opening for the lower end thereof, a valve pivoted on the lower end of the receptacle and normally closing said valve, a weight rigidly connected with said valve adapted to keep the receptacle in a normally raised position, a swinging hanger rod having its lower end pivotally connected to the valve and weight, a frame, a bar supported on said rod, means for connecting the upper end of said frame with said weight, whereby downward movement of the receptacle opens the valve to discharge the sand or gravel or other material from the bottom thereof, said swinging hanger rod supporting a part of the weight of the tank.

3. In a settling tank, two parallel horizontal axes of movement, a receptacle supported upon one axis in such manner that the load thereof is substantially between two axes, a discharge valve for the lower end of said receptacle, pivoted thereto, a hanger rod depending from the other axis and pivoted at its lower end to said valve, a weight rigid with said valve, said weight disposed in position to utilize the lower end of

rod as a fulcrum to raise the receptacle and close the valve.

4. In a settling tank, a receptacle mounted to tilt about a horizontal axis, a hanger rod 5 mounted to swing about a stationary axis at its upper end, a link connection between the lower end of said rod and said receptacle, whereby the weight of said receptacle and its load is imparted to said rod as a tensile 10 strain thereon, a valve operated by said link

connection, a counterbalance applied to said link connection to raise the receptacle and close the valve.

Signed by me at Chicago, Illinois, this 10th day of May, 1909.

RAYMOND W. DULL.
